[57] CLAIM

The ornamental design for a pitcher, as shown and
described.

DESCRIPTION

FIG. 1 is a top rear perspective view of a pitcher showing
our new design;

FIG. 2 is a front elevational view thereof.

FIG. 3 is a rear elevational view thereof.

FIG. 4 is a side elevational view thereof; the opposite
side being a mirror image.

FIG. 5 is a top plan view thereof.

FIG. 6 is a bottom plan view thereof.

FIG. 7 is a transverse sectional view taken through line
7—7 of FIG. 5.

FIG. 1

FIG. 3

FIG. 5

FIG. 6
